UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

DIVERTIBLE BALLAST-CAR.

1,256,107.

Specification of Letters Patent. Patented Feb. 12, 1918.

Application filed August 6, 1917. Serial No. 184,613.

To all whom it may concern:

Be it known that I, ARGYLE CAMPBELL, a citizen of the United States, residing at Chicago, in the county of Cook and State of Illinois, have invented a certain new and useful Improvement in Divertible Ballast-Cars, of which the following is a full, clear, concise, and exact description, reference being had to the accompanying drawings, 10 forming a part of this specification.

This invention relates to improvements in divertible ballast cars.

Objects of the invention are to provide a hopper car more particularly adapted for use as a ballast car and wherein the load-carrying capacity of the car is increased as compared with former constructions; the amount of material employed is decreased as also the cost of fabrication; and wherein 20 the dumping of all the ballast between the rails, when the car is employed for center dumping, is insured, the present invention being in the nature of an improvement upon my prior Patent No. 1,174,677 of March 7, 25 1916.

In the drawing forming a part of this specification, Figure 1 is a transverse, sectional view of a car embodying my improvements, the section of the left hand portion of 30 the car being taken through the center of a hopper and the section of the right hand portion of the car being taken through the end of one of the hoppers. Fig. 2 is a part horizontal section, part top plan of a portion 35 of the car at one end of the hopper section of the car and showing more particularly the arrangement of the door operating mechanism. Figs. 3 and 3^a represent a broken sectional view at the ends of the 40 hopper section to more clearly illustrate the operating mechanism for the center dumping doors. Fig. 4 is a side elevational view of a portion of the car at one end of the hopper section. And Fig. 5 is a partial side 45 elevational view of a portion of the car opposite one of the diaphragms between two of the hoppers.

The improved car is of that type employing a hopper section intermediate the trucks, 50 the hoppers being extended longitudinally on either side of the center sill, there being preferably six hoppers on each side.

In constructing the car, I employ a single

center sill 10 which is preferably in the form of an I-beam to thereby obtain a center sill 55 of minimum width consistent with the necessary strength and the purpose of which will more clearly appear hereinafter. In addition to the center sill 10, the car is provided with side walls 11—11, side stakes 12—12 60 and pressed channel-shaped diaphragm members 13.

Each of the hoppers has a downwardly and inwardly inclined hopper bottom sheet 14; a downwardly and outwardly inclined 65 hopper bottom sheet 15, the latter being secured at their upper edges to the web of the I-beam 10 and beneath the upper flanges thereof, as indicated at 16; end hopper sheets 17, the latter being secured near the 70 middle of the channel diaphragms 13 so that the latter are employed to form portions of the hoppers and thus save material; a side dumping hopper door 18 hinged along its upper edge, as indicated at 19, to the under 75 side of the hopper sheet 14; and a center dumping hopper door 20 hinged along its upper edge, as indicated at 21, to the lower under side of the hopper sheet 15. Each set of hopper doors 18 and 20 is provided 80 with meeting flanges 22 and 23 at the bottom edges of the doors and beneath the meeting edges of the doors is disposed a longitudinally extending diverting partition 24 which is preferably in the form of an angle, 85 the angle 24 being carried by suitable brackets 25 attached to the end hopper diaphragm members 17. The hopper bottom sheets 14 and 15 are suitably braced at their bottom edges as by angles 26—26, the bottom edges 90 of the hopper doors by Z-bars 27—27 and the upper edges of the hopper doors by angles 28—28. As clearly appears from Fig. 1, the meeting edges of the doors of the hoppers are located in a vertical plane 95 well within the rails 29 so that, upon opening of the center dumping doors 20, the gravel or other material will be dumped well within the rails and prevent any of the material from falling outside or on the rails. 100

When the car is used for dumping ballast or other material between the rails, it is desirable to operate the center doors in unison, and for this purpose I provide the following mechanism: On each side of the car is a 105 longitudinally extending operating shaft

30, the shafts 30 being mounted in suitable brackets 31—31 carried by the diaphragm members, it being noted that the shafts 30 are disposed entirely below the diaphragm 5 members so that it is unnecessary to slot or cut the diaphragm members, thus saving considerable labor in the manufacture of the car. From each of the shafts 30 extend a plurality of connections for the hopper doors, there being one more set of connections than there are number of center dumping doors on each side of the car, that is, there will be connections from the shaft 30 at each end of the hopper section and 10 connections between each pair of center dumping doors. Each of these connections includes a hook-shaped link 32 pivotally connected to the hopper door, as indicated at 33; a short link 34; an additional link 35, 15 the link 35 being pivotally connected, as indicated at 36, to an arm 37 carried by a drum rigidly secured to the shaft 30. The connections above described are of a well known form and are so arranged that when 20 the doors are in closed position, tendency to rotate the shaft 30 in an unwinding direction is eliminated. At one end of the hopper section, as shown most clearly in Figs. 3 and 3^a, the shafts 30—30 are provided with 25 worm gears mounted in housings 38, the worm gears meshing with worms mounted in housings 39, the worms being carried by a transverse operating shaft 40 which is extended to one side of the car, as shown most 30 clearly in Figs. 3 and 4. At its end, the shaft 40 is provided with the usual ratchet wheel 42, squared end 43 by which it can be turned, and coöperating with the ratchet wheel 42 is a pawl 44 and a locking dog 45. 35

40 As will be apparent, the worm and worm gear connection between the shaft 40 and shafts 30—30 will automatically lock the shafts 30 in any desired position so that the degree of opening of the center dumping doors 20 can be adjusted and maintained as desired, both sets of doors 20 being operated simultaneously and uniformly.

45 Each set of side dumping doors 18 is operated independently and for that purpose I provide the following mechanism: Secured to the lower flanges of the center sill 10 at the ends of the hopper section and intermediate each pair of hoppers, are depending hanger brackets 46 each of which is provided with a pair of bearings 47—47. Mounted in said bearings are two longitudinally extending operating shafts 48—48, one for one set of side dumping doors and the other for the opposite set of side dumping doors. From each shaft 48 to the set of side dumping doors 18 on the same side of the car extend sets of link connections similar to the link connections previously described in connection with the center dumping doors, the elongated hook-shaped link mem-

bers 49—49, of which are most clearly designated in Fig. 1. In order to economize the material required for the hanger brackets 46, and also to economize space, the link connections to the side dump doors on one side 70 of the car are located on one side of the bracket and the link connections to the side dump doors to the opposite side of the car are located on the opposite side of said bracket, as clearly appears from Figs. 1 and 75 2. At one end of the hopper sections, one of the shafts 48 is extended and mounted in a bearing 50, as indicated in Fig. 2 and on the extended section is provided with a pair of sheave wheels 51—51 over which run 80 chains 52—52, the chains 52 being carried at the side of the car by sheave wheels 53—53 mounted on a stud shaft 54 extended parallel to the side of the car. Said stud shaft 54, as appears most clearly from Figs. 85 1 and 3^a, is provided at its end with a ratchet wheel 55 having the pawl 56 coöperable therewith. The stud shaft 54 is provided with suitable double-acting pawl and ratchet mechanism, as indicated conventionally at 57 in Fig. 1, and adapted to be operated by a lever 58 in a well known manner. One shaft 48 is operated by the chains 52 at 90 one end of the hopper section and the other shaft 48 at the opposite end of the hopper 95 section, Fig. 2 being illustrative of both ends, depending upon the manner in which it is viewed. As shown in Figs. 4 and 5, where the hook-shaped links 49 are located at the ends of the hopper section they are connected to extension brackets 59 carried by the hopper doors 18 and where the links 49 are located between a pair of hoppers, they are pivotally connected to cross brackets 60 which are riveted to each adjacent pair of 100 doors 18 so that each set of doors 18 on each side of the car will be operated as a unit. By employing a single narrow center sill, as illustrated in the drawings, the hopper bottom sheets 15—15 can be brought very 110 close together thus lowering the position occupied by the downwardly and outwardly inclined hopper sheets and adding to the capacity of the hoppers. Furthermore, the location specified of the hopper sheets 15 115 serve to bring the meeting edges of the sets of hopper doors 18 and 20 nearer the center line of the car to thereby insure dumping of the load well within the rails. The arrangement of center sill construction also permits of the operating shafts 48—48 being brought closely together to economize space and permit ample opening movement of the doors 20—20 and furthermore, the location of the shafts 48 below the center sill eliminates the necessity of cutting or recessing any of the diaphragm members. The employment of the single center sill and portions of the diaphragm members 18 as parts 120 of the ends of the hoppers materially 125 de- 130

creases the amount of material necessary in the car while at the same time providing the increased capacity, as above described.

Although I have herein shown and described what I now consider the preferred manner of carrying out my invention, the same is merely illustrative, and I contemplate all changes and modifications that come within the scope of the claims appended hereto.

I claim:

1. In a car of the character described, the combination with a car body having a single center sill and longitudinally arranged sets of hoppers on each side of the center sill, of hinged center dump hopper doors for each set of hoppers; longitudinally extending operating shafts for said doors arranged on the outer sides of said hoppers; side dumping hopper doors for each set of hoppers; and longitudinally arranged operating shafts for the side dumping doors located between the hoppers.

2. In a car of the character described, the combination with a car body having an I-beam center sill and longitudinally arranged sets of hoppers on each side thereof, each of said hoppers including a downwardly and outwardly inclined hopper bottom sheet secured to the web of said center sill; of side dumping hopper doors for said hoppers; center dumping hopper doors for said hoppers; mechanism for operating the center dumping hopper doors of both sets of hoppers simultaneously; and mechanism for operating the sets of side dumping hopper doors independently.

3. In a car of the character described, the combination with a car body having longitudinally arranged sets of hoppers on each side of the center sill thereof; each hopper of each set having a pivoted side dumping door and a pivoted center dumping door, the side and center dumping doors of each hopper having meeting edges located in a vertical plane inside of the car rails; of mechanism for operating said doors; and longitudinally extending diverting partitions disposed beneath the meeting edges of the doors of each

set of hoppers, each diverting partition comprising an angle iron with the flanges thereof inclined downwardly.

4. In a car of the character described, the combination with a car body having longitudinally arranged sets of hoppers on each side of the center sill, the center sill comprising a single beam; of pivoted side dumping doors for said hoppers; pivoted center dumping doors for said hoppers; mechanism for operating the center dumping doors including longitudinally extending shafts disposed on the outer sides of the hoppers; and mechanism for operating the side dumping doors including a pair of longitudinally extending shafts mounted below said center sill.

5. In a car of the character described, the combination with a car body having a center sill and diaphragm members, the car body being provided with sets of longitudinally arranged hoppers on each side of the center sill, each hopper having a side dumping door and a center dumping door; of mechanism for operating all of said doors, said mechanism including four longitudinally arranged shafts, all of said shafts being located below the diaphragms and two of them between the hoppers and beneath the center sill.

6. In a car of the character described, the combination with a car body having an I-beam center sill and longitudinally arranged sets of hoppers on each side of the sill; of pivoted side dumping hopper doors; mechanism for operating said side dumping doors, including a pair of longitudinally arranged operating shafts, brackets secured to the under face of said center sill and in which said shafts are mounted; center dumping doors for said hoppers; and mechanism for operating the center dumping doors simultaneously, said mechanism including a pair of longitudinally arranged shafts located on the outer side of said hoppers.

In witness that I claim the foregoing I have hereunto subscribed my name this 30th day of July 1917.

ARGYLE CAMPBELL.
